UNITED STATES PATENT OFFICE.

IMOGEN S. PIERCE, OF PHILADELPHIA, PENNSYLVANIA.

GARMENT-FASTENER.

SPECIFICATION forming part of Letters Patent No. 695,341, dated March 11, 1902.

Application filed September 17, 1900. Serial No. 30,278. (No model.)

To all whom it may concern:

Be it known that I, IMOGEN SOMERFIELD PIERCE, a citizen of the United States, residing in Philadelphia, Pennsylvania, have invented certain Improvements in Garment-Fasteners, of which the following is a specification.

One object of my invention is to provide a garment-fastener whereby the meeting edges 10 of the parts of a garment can be retained in their proper relation to each other without the necessity of fastening either portion of the fastener to the garment.

A further object is to dispense with the use 15 of an exposed or open hook and cause the fastener to lie snugly against the material of which the garment is composed, thus overcoming an objection to the ordinary hook and eye, which project so far from the garment as frequently to interfere with the desired close fit of the same.

My improved garment-fastener can also be constructed so as to retain the parts with a certain measure of elasticity in order to permit them to yield when subjected to undue 25 strain and to return to their normal condition when such undue strain is removed. The fastener can also on occasion be used as a suspending device for certain purposes.

30 In the accompanying drawings, Figure 1 is a perspective view of my improved garment-fastener. Fig. 2 is a sectional view of portion of a garment with the fastener applied thereto. Figs. 3 and 4 are respectively front 35 and back portions of the same. Fig. 5 is a perspective view illustrating another form of fastener embodying my invention; and Figs. 6 and 7 represent, respectively, in perspective and in sectional elevation a hook-and-eye 40 fastening embodying certain features of my invention.

The fastener shown in Figs. 1 to 4 consists of a piece of wire, sheet metal, or other available material bent, cut, or shaped so as to 45 form a shank or connecting-bar 1, terminating in opposite hooks or loops 2, which face each other and are preferably spread or widened, as shown in Fig. 3, so that after being passed through buttonholes 3 in the 50 meeting portions of the garment they cannot be accidentally disengaged therefrom. The

fastener will thus serve to retain the two portions of the garment in their proper relation to each other, and as the shank or bar 1 and the opposite hooks 2 lie snugly against the 55 opposite faces of the garment there are no projecting portions to catch in other portions of the apparel, nor is the bulk of the fastener such as to prevent the close fitting of the garment to the person or the close fitting 60 of another garment over the same.

To increase the bearing-surface of the cross-bar or shank 1 of the fastener, the latter may be spread or widened, as shown at 4 in Fig. 4, at points corresponding with the widened 65 portions of the hooks 2, and in some cases the fastener may be made of resilient material, so that this cross-bar or shank is free to expand and contract, and will thus permit the two parts of the garment to spread apart when 70 subjected to undue strain or cause them to return to their normal position when such strain is removed.

In that form of fastener shown in Fig. 5 the loops or hooks 2 are on opposite sides of the 75 bar or shank 1 instead of being upon the same side of the bar, as in the fastener shown in Fig. 1.

In applying my invention to a hook-and-eye fastening for use in connection with button-holed portions of garments I adopt the construction shown in Figs. 6 and 7, in which the bar 1 has but a single hook 2 for engaging with one buttonhole, one of the loops 4 of the bar 1 serving as an eye for engagement with 80 the hook 5, which constitutes the bent end of a bar 6, having a widened loop 7 and a widened hook 8 for engagement with the buttonhole opposite to that which is engaged by the hook 2.

In all cases it is preferable, although not 90 absolutely necessary, to twist the wire at the juncture of the hooks and loops, as at 9, for instance, so as to prevent spreading of the fastener at these points.

The fastener shown in Figs. 1 to 4 comprises but a single piece instead of the two elements of an ordinary hook-and-eye fastening, and even when the fastener is made in the form of a two-part or hook-and-eye fastening it is adapted to be used in connection 95 100 with ordinary buttonholes, so that it can be readily applied or removed, no sewing of any

part of the fastener to the garment being required.

The device may also be used in some cases as a suspension-hook—as, for instance, in supporting a sling or hammock in a bath-tub for the treatment of a patient in certain diseases where a long-continued submergence of a portion of the body is required. In such case it is necessary simply to adapt one hook to the edge of the tub and the other to a buttonhole or eye at the corner of the sling.

Having thus described my invention, I claim and desire to secure by Letters Patent—

15 1. The within-described garment-fastener consisting of loops connected by a double bar or shank and projecting inwardly but not outwardly beyond the ends of the latter so as to form hooks, said hook portions being composed of continuous runs of the material forming the fastener, substantially as specified.

20 2. The within-described garment-fastener, consisting of loops connected by a double back bar or shank and projecting inwardly but not outwardly beyond the ends of the latter so as to form hooks facing each other, said hooks being formed of continuous runs of the material composing the fastener and being lat-

erally spread or widened, substantially as specified.

3. The within-described garment-fastener consisting of a double bar or shank terminating in opposite hooks facing each other, said hooks being formed of continuous runs of the material forming the fastener, and being laterally spread or widened, each member of said bar or shank being bent so as to provide laterally spread or widened portions underlying said hooks, substantially as specified.

4. The within-described garment-fastener consisting of a continuous double bar or shank terminating in opposite bent ends forming hooks facing each other, said hooks being formed of continuous runs of the material of which the fastener is composed, the material being twisted at the point where the ends are bent over to form the hooks, substantially as specified.

In testimony whereof I have signed my name to this specification in the presence of two subscribing witnesses.

IMOGEN S. PIERCE.
